UNITED STATES PATENT OFFICE.

JOSEPH LEITSCHUH, OF CHICAGO, ILLINOIS, ASSIGNOR OF ONE-THIRD TO JENS P. NIELSEN AND ONE-THIRD TO CARL C. NIELSEN, BOTH OF CHICAGO, ILLINOIS.

PENCIL-CLASP.

1,085,386.

Specification of Letters Patent.

Patented Jan. 27, 1914.

Application filed December 23, 1912. Serial No. 738,354.

To all whom it may concern:

Be it known that I, JOSEPH LEITSCHUH, citizen of the United States, residing at Chicago, in the county of Cook and State of Illinois, have invented certain new and useful Improvements in Pencil-Clasps; and I do hereby declare the following to be a full, clear, and exact description of the invention, such as will enable others skilled in the art 10 to which it appertains to make and use the same.

This invention has for its object to provide a novel pencil clasp adapted to permit the pencil to be secured against accidental 15 removal from the pocket, and which furthermore, permits the mounting on the pencil of miniature photographs, calendars or other desirable matter, and consists in the features of construction and combinations of parts 20 hereinafter fully described and particularly claimed.

In the accompanying drawings illustrating a suitable embodiment of the invention: Figure —1— is a view in elevation of a 25 pencil equipped with a clasp embodying the invention. Fig. —2— is a transverse section of the same on the line 2—2 of Fig. —1—. Fig. —3— is a view in elevation taken from a diametrically opposite point 30 to that shown in Fig. —1—. Figs. —4— and —5— are views in elevation of modified forms of construction. Fig. —6— is a detail sectional view on the line 6—6 of Fig. —5—.

The particular object of my invention is 35 to provide a device for use on pencils, pen-holders, fountain pens and the like, whereby miniature photographs, small calendars, or any other desirable similar matter may be 40 displayed on the same.

In its preferred embodiment the invention comprises a split sleeve 1 made of an elastic sheet metal which is adapted to receive the pencil or similar device 2, and be 45 frictionally held in place thereon in the usual and well-known manner. The said sleeve 1 is provided at one end with a projection 3 equipped at its free end with a

spherical point 4 between which and the body of the pencil the wall of a pocket is 50 adapted to be received and engaged.

My invention resides more particularly in the member 5 comprising what may be termed an elastic split cylindrical sheet metal frame which is adapted to receive the 55 sleeve 1 or the pencil 2 and yieldingly engage the same whereby it will be held in place thereon. The said member 5 is of skeleton form, that is to say, the middle portion thereof is entirely cut away between the 60 sides and ends thereof to provide a large opening 6. The portions of said member bordering the opening are offset relatively to the outermost edge portion so as to form flanges 7 and 8 disposed inwardly of the 65 edge portions of said member which are some distance removed from the cylindrical plane of said edge portion. Between said flanges 7 and 8 and the surface of the sleeve 1 or pencil 2 a plurality of thin sheets 9 and 70 10 are adapted to be received, the former thereof consisting of a miniature photographic print, calendar or the like, and the latter preferably of a transparent celluloid or similar elastic transparent material which 75 is adapted to cover the sheet 9. The said member 5 may be used as an adjunct to the clasp 1 with its projection 3 and spherical point 4, or to any similar sleeve adapted to receive the pencil 2, such for example, as 80 removable point-protecting sleeves, and the like, or the same may be mounted directly upon the pencil, as shown in Fig. —4—.

The construction may be further modified as shown in Fig. —5— in which the member 85 5 is equipped at one end with a projection 11 similar to the projection 3 and which is equipped with the spherical point 12 corresponding to the point 4. In order that said member 5 may more completely surround the 90 pencil 2 the same may be provided on its opposed edges with projections 13.

The device is simple, cheap, ornamental and useful in that it enables matter intended for ready reference to be displayed on the 95 pencil, or the like.

I claim as my invention:

A loss-preventing device comprising a sleeve-like member split to yieldingly embrace a pencil and having an opening, said member including a flanged portion bordering said opening and forming the walls thereof, the said portion being off-set outwardly providing a free space therein, a retaining member carried by the sleeve-like member,

and a transparent sheet positioned immediately beneath said flanged portion. 10

In testimony whereof I have signed my name in presence of two subscribing witnesses.

JOSEPH LEITSCHUH.
